UNITED STATES PATENT OFFICE.

MILLARD P. OSBOURN, OF MERCHANTVILLE, NEW JERSEY, ASSIGNOR TO WARREN WEBSTER & COMPANY, A CORPORATION OF NEW JERSEY.

STEAM-HEATING APPARATUS.

1,185,128.

Specification of Letters Patent. Patented May 30, 1916.

Application filed July 3, 1908. Serial No. 441,749.

To all whom it may concern:

Be it known that I, MILLARD P. OSBOURN, a citizen of the United States, and resident of the city of Merchantville and county of 5 Camden, State of New Jersey, have invented an Improvement in Steam-Heating Apparatus, of which the following is a specification.

My invention has reference to steam heating apparatus and consists of certain improvements fully set forth in the following specification and shown in the accompanying drawings which form a part thereof.

The object of my invention is to provide 15 a construction of low pressure steam heating system especially adapted for small buildings, in which an efficient utilization of the steam may be had in the radiators by the elimination of the air and water of 20 condensation therefrom, and the said water of condensation returned to the boiler.

My object is also to provide a low pressure system of steam heating, in which the air expelled from the radiators, may freely 25 escape to the atmosphere and be moved from the circulation, while preventing any excess of air being admitted into steam under the influence of a vacuum being created in the radiators when supplying steam 30 to the radiators when in a cold condition.

My invention consists in the employment of radiators, supply and return pipes, means for regulating the supply of steam to the radiators, and automatic valves between 35 the radiators and return pipes for permitting the escape of water and air therefrom into the returns while restricting or substantially preventing the escape of steam, and automatic means for permitting 40 the escape of the air from the return pipes into the atmosphere while preventing an inflow of air thereto.

My invention further consists in the heating apparatus above specified when combined 45 with automatic means for transferring the water of condensation from the return pipes to the boiler without permitting pressure from said boiler to extend into the return pipes.

My invention further consists in the employment in a low pressure steam heating system of an air relief pipe connecting with the return pipe at a point above where the water of condensation collects for return, to 55 the boiler, and automatic valves between the

radiators and return pipe for permitting the escape of water and air into the return pipe but restricting or preventing the escape of steam from the radiators.

My invention also comprehends details of 60 construction which, together with the features above specified, will be better understood by reference to the drawings, in which:—

Figure 1 is an elevation representing diagrammatically a steam heating system embodying my invention; Fig. 2 is a sectional elevation of the relief valve for the air vent pipes of the return pipes; Fig. 3 is a cross section of one of the automatic return 70 valves, Fig. 4 is a diagrammatic elevation illustrating a modification of my invention, and Fig. 5 is a diagrammatic elevation illustrating another modification of the invention. 75

2 are the radiators, and 3 are the steam supply pipes leading from the boiler or steam generator 5, from which steam is delivered to the radiators by suitable valves 4, by which varying quantities of steam may 80 be supplied to the radiators.

6 are the return pipes and connect with the radiators by short branches containing automatic return valves 7, which are so constructed as to permit the discharge of accumulated water of condensation from the radiators into the return pipes, as well as the escape of air from the radiators into the return pipes, while restricting or preventing the escape of steam from the radiators 90 whereby all, or practically all, of the steam which is supplied to the radiators may be condensed therein to impart its latent heat to the surrounding atmosphere and insure an efficient operation of the system. The 95 water of condensation which passes into the return pipe 6 through the return valves, is delivered to the pipe 12 in the basement, and transferred through a return trap 14 by a pipe 15 to the boiler or generator 5 100 by gravity. The return trap 14 may be of any suitable construction, there being numerous traps upon the market which may be employed for this purpose, therefore that shown is by way of illustration only. In 105 the particular construction illustrated, the water passes from the pipe 12 through a check valve 13, and into the body of the trap where it accumulates. As the water rises, it lifts the float 19 which, through 110

the trap 14, opens the valve 13, and permits the water to pass through the pipe 12 into the body of the trap 14, where it accumulates. As the water rises, it lifts the float 19 which, through 110

suitable lever and link connections 20, opens a steam valve 18, controlling the supply of steam from the boiler through the pipe 17 into the top of the trap 14. Upon the entrance of the steam, equilibrium is established in the pressures of the trap and the boiler, and the water then flows from the trap body through the check valve 16 and pipe 15 into the boiler, until the level in the trap becomes lowered sufficiently to cause the steam valve 18 to be closed. The trap 14 is arranged at or above the level of the water in the boiler and, where the space admits of it, would preferably be arranged somewhat above the water level of the boiler so as to more equally discharge into the boiler when the equilibrium in pressures is established. The check valve 18 prevents steam from passing backward into the return pipes and the pipe 12 will collect and hold the water of condensation during the time that the steam is admitted to the trap.

From convenient points in the return pipe 6, I connect air pipes 8 for relieving the return pipes of the air which they may receive from the radiators, and these pipes 8 may discharge directly to the atmosphere above the radiators, and preferably they discharge through a pipe 9 and a relief valve 10 therein. This relief valve is shown in Fig. 2 and is made in the form of a check-valve in which the valve piece 11 is preferably hung in such a manner that it offers practically no resistance to the escape of the air, while being in position to prevent any inflow of air into the system should a partial vacuum be created therein when turning steam on to one or more of the radiators when in a cold state. As shown, this relief valve comprises a valve piece pivoted above the valve seat and hanging by gravity so as to rest substantially against or adjacent to the seat without any pressure. However, while I prefer this construction of relief valve shown in Fig. 2, any check-valve or other device which will permit the escape of air without material back pressure and while preventing the inflow of air, may be used in place of the preferred form. It is also evident that the sealing of the outlet of the air pipe 9 under the normal operations is not essential so long as the valve device will operate automatically to be responsive to check any material inflow of air into the system in case of the existence of a partial vacuum therein, as aforesaid.

The automatic valve 7 illustrated, is excellently adapted for the purposes of my invention. The general construction of this valve is shown in Fig. 3. It comprises the body part having a valve seat 25 upon which a valve piece 26 seats. The valve piece is tubular and is provided with a float 23, the upper part of the tubular valve piece being open. A stem 28 from the cap or bonnet of

the valve extends down through the tubular valve piece and guides it, while at the same time, forming an annular duct of small sectional area. There may be, surrounding the float 23, an apron as indicated by the dotted lines at 27. In the operation of this valve the air may be caused to escape into the return pipe through the annular duct between the stem 28 and the tubular piece 26 but, this being a capillary duct, it restricts the escape of steam by causing it to condense and seal the said duct to a greater or less extent whenever the steam attempts to pass. The water of condensation from the radiator collects in the lower part of the valve body and when it accumulates it lifts the float and with it, the valve piece, to permit the water to escape through the valve seat 25. Before all the water has passed through, the valve piece again seats itself and the valve operates as before. From this it will be seen that, the air and water are removed from the radiator as fast as they accumulate, while the steam is prevented from escaping in any material quantities. Furthermore it is evident that air valves on the radiators may be dispensed with. It will also be seen that while the water is intermittently removed at intervals and only when it sufficiently accumulates, the air is being removed at all times as fast as it is liberated within the radiator. We have, therefore, a continuous means for removing the air and the intermittent means for removing the water and a positive means for restricting or preventing the escape of steam, all of which is important to the most successful operation of this invention.

While I have described the preferred form of return valve for use in connection with my improved heating system, I do not restrict myself to any particular character of automatic return valve, as long as it permits the escape of the air and water into the return pipe, while restricting or preventing the escape of steam from the radiators, as any valve or device capable of performing these functions may be employed in the heating system intended to be defined in this application.

There is a possibility of the relief valve 10 requiring some attention from time to time, and moreover as it may be inconvenient to locate it at the top of the house or building, I may arrange the said relief valve in the basement substantially in the manner indicated in Fig. 4. In this modification, I prefer the return pipe 6 to drain into a tank 21 from which the water may be delivered to the boiler through the steam trap 14. From the upper part of the tank 21 the relief pipe 9 may extend and connect with the relief valve 10, the said relief valve discharging into an air pipe 22 leading upward to the roof or other place communicating with the atmosphere. The lower part

of the pipe 22 may be connected with one leg of a U shaped water seal pipe 24, the other leg of the said seal being connected with the tank 21. In this manner the water 5 of condensation which might, under some conditions, run down the pipe 22, is delivered to the tank 21 through the water seal 24 thereby preventing the water accumulating against the discharge side of the relief 10 valve 10 and impressing thereon a back pressure and also a resistance by freezing. The water seal 24 is made sufficiently deep to require a greater vacuum within the system to break it than would occur in said system under the conditions hereinbefore referred to, 15 and it would therefore prevent any ingress of air.

While the delivery of the water of condensation from the air or relief pipe 22 to the return pipe or tank 21 may be accomplished through a water seal as at 24 such seal may be substituted by a float trap as indicated at 24^a in Fig. 5, as such a trap will allow the accumulations of water to 25 pass into the tank 21 while preventing any passage of air thereto in case of a partial vacuum temporarily existing in the return pipes from causes hereinbefore mentioned.

I have shown the air relief pipe connecting with the return pipe directly or indirectly through the tank 21 above where the water ordinarily collects adjacent to the steam trap so that the air may freely escape without being interfered with by the water 35 of condensation; and this air pipe is preferably provided with an automatic device to prevent the inflow of air into the system.

While the air which may be in the trap 14 may find its way into the boiler 5 through a pipe 17 when the valve 18 opens and the steam admitted to the trap, it is preferable to provide means for allowing the air to escape to a place of less resistance as is customary in such traps. This may be accomplished by employing the air pipe 30 leading from the trap and through which the air may be driven when the valve 18 is opened to admit steam. Ordinarily this air escapes to the atmosphere, but I prefer to 45 have it pass into the return pipe 12 as shown in Fig. 1 or into the tank 21 as shown in Fig. 4. I also prefer to arrange in said pipe 30 a check valve 31 which will prevent the air passing in a reverse direction or into the 50 trap, for the following reasons: When the water within the trap has been caused to flow into the boiler the valve 18 is closed and as the pressure within the trap is lowered the water from the returns flows into it 55 and condenses the remaining steam and tends to produce a partial vacuum within the trap, but this is made effective for speedily drawing the water into the trap because the check valve 31 in the air pipe 60 prevents air being drawn into the trap

through the air pipe, which would otherwise be the case with traps as ordinarily constructed. This is useful in securing a speedy return of the water of condensation to the boiler and especially so in starting up 70 the plant and in very cold weather, when much water of condensation is produced. Therefore, while the pipe 30 and check valve 31 are essential their employment makes the apparatus more responsive.

75

While I have shown the use of a steam trap for returning the water from the return pipe into the boiler, it is to be understood that any other suitable means adapted for such purpose may be employed in lieu thereof or in the embodiment of my invention into commercial use.

80

In the foregoing description of my invention I have assumed a normal operation wherein the pressure carried by the boiler, 85 while low, is nevertheless a material one and in which the pressure in the return pipe is atmospheric pressure. In case, in very small equipments, the steam pressure was practically that of the atmosphere, then in such 90 event the steam trap 14 need not be used or what amounts to the same thing the steam valve 29 may be closed so that the water from the return pipe 12 may return to the boiler by gravity, the rest of the system operating as hereinbefore described.

95

While I prefer the construction shown as being excellently adapted for the purposes of my invention, the details thereof may be modified or varied without departing from 100 the spirit of my invention.

Having now described my invention, what I claim as new and desire to secure by Letters Patent, is:—

1. In a low pressure steam heating system 105 the combination of radiators, a boiler, a steam supply pipe from the boiler to the radiators, valves to control the supply of steam to the radiators, a return pipe from the radiators for returning the water of condensation 110 from the radiators, automatic means for returning the water from the return pipe to the boiler, relief devices for permitting the air to escape from the return pipe directly into the atmosphere while preventing 115 air in material quantities entering therein consisting of an air pipe in communication with the return pipe above where the water collects and having therein an outwardly opening check valve, a water sealing means 120 communicating with the air pipe beyond the check valve for delivering the water from said air pipe to the return pipe without passing through the check valve, and automatic return valves between the radiators 125 and return pipe for permitting the passage of air and water but preventing the escape of steam into the return pipe.

2. In a steam heating system, the combination of a boiler, radiators, a supply pipe 130

leading from the boiler to the radiators, a return pipe leading from the radiators, return valves between the radiators and return pipe for permitting the passage of water 5 and air but restricting the flow of steam, a closed tank into which the return pipe discharges, a trap controlled by the level of the water therein for intermittently delivering the water from the closed tank to the 10 boiler, an air vent pipe leading to a point above the closed tank and provided at the bottom with two connections opening into the said tank, one of said connections being provided with a check valve which permits 15 air to pass from the tank into the air pipe but prevents the flow of air in the reverse direction, and the other of which connections comprises a water seal arranged at a lower elevation than the check valve for returning the water of condensation from the 20 air pipe into the closed tank.

3. In a steam heating system the combination of a boiler, radiators, a supply and a return pipe leading from the boiler to said 25 radiators and from said radiators to the boiler, respectively, said parts forming a circulatory system, an air relief pipe communicating with the return pipe above the normal water level therein, said pipe being provided with a check valve for preventing the 30 return of air therethrough and being freely open to the atmosphere beyond said check valve, and a sealed drip pipe communicating with said air relief pipe beyond said 35 check valve for returning the water of condensation from said air relief pipe to the circulatory system.

4. In a steam heating system, the combination of a boiler, radiators, a supply pipe 40 and a return pipe leading from the boiler to said radiators and from said radiators to the boiler, respectively, said parts forming a circulatory system, an air relief pipe extending above the normal water level in the 45 system and opening to the atmosphere and providing two passages communicating with

the return pipe of the system one of which is arranged above the normal water level in the return pipe and permits air to pass therefrom into the air relief pipe and the 50 other of which receives water from the air relief pipe and returns it to the return pipe, a check valve arranged in the passage which is above the normal water level in the return pipe to permit the passage of air from the 55 return pipe into the air relief pipe but preventing passage of air in the opposite direction, and sealing means arranged in the other passage communicating with the air relief pipe which permits the passage of 60 water from the air relief pipe into the return pipe of the system but prevents the passage of air in the opposite direction.

5. In a steam heating system, the combination of a boiler, radiators, a supply and 65 a return pipe leading from the boiler to said radiators and from said radiators to the boiler, respectively, said parts forming a circulatory system, an air relief pipe communicating with the return pipe above the 70 normal water level therein, said pipe being provided with a check valve for preventing the return of air therethrough and being freely open to the atmosphere beyond said check valve, a sealing means located 75 between the lower part of the air relief pipe and the circulatory system and communicating with the air relief pipe beyond the check valve therein and arranged for returning the water of condensation from said 80 air relief pipe to the circulatory system but preventing the inflow of air thereto, and a float controlled means for intermittently returning the water from the return pipe to the boiler.

In testimony of which invention, I have hereunto set my hand.

MILLARD P. OSBOURN.
